UNITED STATES PATENT OFFICE.

CHRISTIAN GULBRANSEN, OF CHICAGO, ILLINOIS, ASSIGNOR TO GULBRANSEN COMPANY, A CORPORATION OF ILLINOIS.

PIANO KEY.

Application filed November 2, 1922. Serial No. 598,534.

My invention relates to piano keys, and particularly to improvements in keys for player pianos.

A conventional practice in grand piano player construction is to operate the piano action by the player action through the medium of the piano keys, i. e., to place the stack of pneumatics below the level of the keys and to have the pneumatics operate the piano action through the medium of fingers or rods which push upwardly on the inner ends of the piano keys. In this arrangement the player pneumatics must operate against the inertia and friction of the entire key, including the ivory faced finger ends constituting the keyboard.

It is the fundamental object of the present invention to avoid the above disadvantages of operating the entire key, preferably by articulating the key so that only the inner portion thereof will be actuated by the pneumatics, the whole key, however, operating in the usual way when operated by hand. The inner portion is of very small inertia and friction so that it imposes a minimum deterrence to the operation of the player pneumatics. The articulated key also avoids the objectionable appearance of the numerous keys rising and falling along the keyboard during the operation of the player mechanism.

Other objects of the invention are concerned with the improved form of joint for articulating the key. The joint must be easy working, inexpensive and exceedingly compact because of the close nesting of the keys. It is furthermore desirable that the articulated portion of the key which strikes the piano action move from substantially the same center and strike at substantially the same radius when actuated by the player action as when actuated during manual playing at the keyboard.

Referring to the accompanying drawing illustrating a preferred embodiment;

Figure 1 is a fragmentary sectional view through a key-bed, illustrating the use of my improved key;

Fig. 2 is a fragmentary elevational view of a modified form of joint; and

Fig. 3 is a plan view of the same.

The keys which are designated 6 in their entireties, are pivotally mounted on the bed 7 upon hinge pins 8. The ivory surfaced finger ends 9 play between the front board

11 and the strip 12 running along the edge of the bed 7. The vertical motion of the finger end of each key is guided upon an upright guide pin 10 which engages in a slotted felt-lined hole 10' in the finger end. 60 This is all conventional practice and needs no detail description. It should be remarked, however, that the friction of the guide pin 10 in the hole 10, and the finger end 9 in the keyboard, is sufficient to support the key in its raised position against the action of gravity.

The inner end of the key plays between the piano action, illustrated at 13, and the player action, illustrated fragmentarily at 70 14. The piano action 13 is operated by a capstan screw 15 striking the actuating member 16 and actuating the hammer 17 in the usual manner.

The stack of pneumatics 14 is supported below the bed 7, the finger extension 18 of each pneumatic 19 being adapted to engage a rod 21 passing upwardly through the guide block 22. The upper end of each rod 21 carries a felt button 23 adapted to strike 75 the inner end of the key and thrust the same upwardly, upon the actuation of the corresponding pneumatic 19.

In the conventional construction the upward thrust of the rod 21 rocks the entire key about the vertical pivot pin 8. In the present construction I divide the inner end of the key into upper and lower halves 24 and 25. The lower portion 25 is a continuation of the main body of the key 6. The upper leaf portion 24 is a section sawed out of the body of the key or otherwise conformed to complete the inner end of the key. This leaf section 24 has a depending tail piece 26 which overhangs the end of the key portion 25 and receives the impulse of the player pneumatic through button 23. The capstan screw 15 is carried in this leaf portion 24. Pivotal motion of the leaf portion 24 towards and away from the key extension 25 is guided by a pin 20 which extends up through a slotted hole 30 in the inner end of the leaf portion. A felt washer 40 between the leaf portion and the key extension prevents noise on the return stroke 100 of the leaf portion back against the key extension. The other end of this leaf portion 24 is hinged or jointed to the body of the key, preferably at a point adjacent to or coincident with the pivotal axis of the key. 110

A sheet metal clip 27 embraces the top and both sides of the end of the leaf portion 24, being secured thereto by pins 28 extending through and riveted over on the sides of the 5 clip. From this clip extends two pivot arms 29, one on each side of the body of the key 6, and these arms have pivotal attachment to the body of the key upon a pivot pin or pins 31. The pin 8 extends up through an 10 opening or slot 32 in the key, which opening is in the nature of a round hole in the bottom of the key, and an elongated slot at the top of the key. The key rocks on this pin over the convex supporting plate 33 which 15 is mounted on the piano bed 7. This is the center of pivotal motion of the capstan screw 15 when the outer end 9 of the key is depressed. By extending the two pivot arms 29 down into proximity to the intersection 20 of the pivot pin 8 with the supporting plate 33, the leaf portion 24 will move from substantially the same center of pivotal motion when actuated by the plunger action. In Fig. 1 a single pivot pin 31 is passed through 25 the pivot arms 29 and body of the key alongside of the upright pivot pin 8. In Fig. 2 the arms 29 are each pivoted to the side of the key by individual short pivot pins 31, which are disposed coincident with the axis 30 of the pivot pin, but neither of which pass through the key.

In the operation of the player action 14 the upward motion of the player rod 21 strikes the tail end 26 of the corresponding 35 key and raises the leaf portion 24, thereby imparting actuating motion to the piano action without having to overcome the inertia and friction of the key proper. The friction at the finger end of the key holds 40 this end up when the leaf portion 24 is raised.

I claim:

1. In a player piano, in combination, a pivot pin and plate, a key element centrally supported thereby, said key element extending with undiminished cross section a short distance past said pin, the cross section being then cut down, a leaf lying on the element beyond said pin, a pivotal connection be-

tween leaf and element substantially on the axis of rotation of said element on its support, said leaf projecting beyond the end of said element, a pneumatic action, connections between said action and leaf engaging the projecting end of said leaf, a piano action, and an operating connection between 55 said leaf and piano action.

2. In a player piano, in combination, a pivot pin and plate, a key element centrally supported thereby, said key element extending with undiminished cross section a 60 short distance beyond said pin, the cross section being then cut down, a leaf lying on the element beyond said pin, and a pivotal connection between leaf and element substantially on the axis of rotation of said element 65 on its support.

3. In a player piano, in combination, a piano action, a leaf, an operating connection between said leaf and said piano action, a key supporting said leaf and pivoted beyond the end thereof, an extension on said leaf pivoting it on an axis substantially in the same vertical plane as the key pivot, and a pneumatic action connected directly to 70 said leaf.

4. In a player piano, in combination, a piano action, a leaf, an operating connection between said leaf and said piano action, a key supporting said leaf and pivoted beyond the end thereof, an extension on said leaf pivoting it on an axis substantially the same as that of the key pivot, and a pneumatic action 75 connected directly to said leaf.

5. In a player piano, in combination, a piano action, a leaf, an operating connection between said leaf and said piano action, a key supporting said leaf and pivoted beyond the end thereof, an extension on said leaf pivoting it on an axis substantially in the same vertical plane as the key pivot, and a pneumatic action connected directly to 80 said leaf, said extension comprising a clip having an arm extending beyond the end of the leaf.

In witness whereof, I hereunto subscribe my name this 18 day of October, 1922.

CHRISTIAN GULBRANSEN.
